UNITED STATES PATENT OFFICE

154,663

DESIGN FOR A GAME BOARD

Raymond L. Culp, Chickasha, Okla.

Application October 1, 1947, Serial No. 141,700

Term of patent 3½ years

(Cl. D34—5)

To all whom it may concern:

Be it known that I, Raymond L. Culp, a citizen of the United States, residing at Chickasha, in the county of Grady and State of Oklahoma, have invented a new, original and ornamental Design for a Game Board, of which the following is a specification, reference being had to the accompanying drawing, forming part thereof.

I claim:

The ornamental design for a game board, as shown.

RAYMOND L. CULP,
